UNITED STATES PATENT OFFICE.

GUSTAV SEGSCHNEIDER, OF YONKERS, NEW YORK.

MACHINE FOR WELTING AND ROUNDING HAT-BRIMS.

No. 900,001.

Specification of Letters Patent.

Patented Sept. 29, 1908.

Application filed March 28, 1908. Serial No. 423,805.

To all whom it may concern:—

Be it known that I, GUSTAV SEGSCHNEIDER, a citizen of the United States of America, residing at Yonkers, in the county of 5 Westchester and State of New York, have invented certain new and useful Improvements in Machines for Welting and Rounding Hat-Brims, of which the following is a specification.

10 This invention relates to an improved machine for welting and rounding hat-brims by which the manual labor in accomplishing the welting and rounding operation is dispensed with and the same accomplished mechanically in a quick and effective manner; and for 15 this purpose the invention consists of a machine for welting and rounding hat-brims which comprises a table, a stationary ring on said table corresponding to the shape of the 20 hat-carrying templet, a welting ring, means for heating said ring when in raised position, means for lowering said ring and forming the welt over the circumference of the templet, and means for imparting a short vertical 25 reciprocating motion to the welting ring.

The invention consists further of certain details of construction and combinations of parts to be hereinafter described and claimed.

30 In the accompanying drawings, Figure 1 represents a front-elevation of my improved machine for welting and rounding hat-brims, showing the welting ring in lowered position locked to the table, Fig. 2 is a detail vertical 35 section on line 2, 2, Fig. 4, drawn on a larger scale, and showing the welting ring in position on the hat-brim before rounding off the edge of the brim, Fig. 3 is a side-elevation of the machine showing the welting ring in 40 raised position for heating the same preparatory to the welting of the brim, Fig. 4 is a plan-view of the table, partly in horizontal section, on line 4, 4, Fig. 3, Fig. 5 is a vertical transverse section of the welting and cutting 45 device, drawn on a larger scale, and Fig. 6 is a plan-view of Fig. 5.

Similar letters of reference indicate corresponding parts throughout the figures.

Referring to the drawings, *a* represents 50 the supporting frame of my improved machine for welting and rounding hat-brims. On the frame *a* is supported a table *a*¹ which is provided with an opening of sufficient size for inserting different sizes of templets *t*, as 55 required for the different sizes of hats. The templets are made of an oval body of wood

for the crown and a corresponding plate of zinc for the brim, the parts being united in any suitable manner. On the table *a*¹ is arranged a stationary ring *b* which corresponds in general shape to the templet, the base of the ring being attached to the table in any suitable manner. Into the ring *b* is fitted a welting ring *d*, which is also made to correspond in shape to the shape of the templet *t* 60 and ring *b*, and which is supported by means of ears *d*¹ at diametrically opposite points to two vertically-guided rods *d*² which are guided in openings of the table *a*¹ and sleeves *a*^x on the frame *a*, and raised or lowered by 65 means of a transverse treadle-rod *r* which is connected by bracket-rods *r*¹ and cross-rod *r*² to the lower ends of the vertically-guided rods *d*²; said treadle-rod, guide-rods and 70 welting ring being counterbalanced by a 75 weight *d*³ which is connected by cords *d*⁴ passing over pulleys *d*⁵ at the under-side of the table with fixed sleeves *d*^x on the rods *d*², as shown clearly in Figs. 1 and 3.

At one corner of the table *a*¹ is swiveled an 80 upright arm *e*, which is bent at right angles at its upper part and then bent in downward direction at its inner end, the downwardly-bent end supporting a hub *e*¹ provided with radial pipes *e*² having discharge-orifices at 85 their ends. The hub *e*¹ is connected by a suitable hose or pipe *e*³ with a supply of gas and air or other heating medium. The hose or pipe *e*³ is provided with a stopcock for turning on or cutting off the supply of gas to 90 the radial pipes or arms. The heating jets emitted by the radial arms *e*² serve for heating the welting ring *d*, which latter is raised so as to encircle the heating arms. After the 95 welting ring is sufficiently heated, the upright arm *e* is swung with the heating arms clear of the table, as shown in dotted lines in Fig. 4, so as to give free access to the table and the hat supported in the templet placed in the opening of the same. At the upper ends of 100 the vertically-reciprocating rods *d*² are arranged, above the ears which connect them with the welting ring, collars *d*⁶, screw-nuts *d*⁷ and helical cushioning springs *d*⁸, which latter are interposed between the ears and 105 collars, so that a certain degree of yielding motion can be imparted to the welting ring, as required by the welting operation.

At the lower part of the frame *a* are arranged, below the cross-rod *r*² connecting the 110 lower ends of the rods *d*², rods *f* which extend to the rear of the frame and which are con-

nected by a transverse pivot rod f^1 at their rear ends, said rod f^1 being connected by a connecting-rod f^2 with an eccentric f^3 on a shaft s , which is supported in suitable bracket-bearings at the upper rear-part of the frame a and which receives rotary motion by a belt-and-pulley transmission from an overhead shaft, electric motor or other source of power. In the lowermost position of the treadle r, r' , the cross-rod r^2 rests on the oscillating lever f , and transmits thereby a quick reciprocating movement to the welting ring, said cross-rod being held against said levers by the pressure of the operator's foot on the treadle-rod r . During this reciprocating motion of the welting ring, it yields sufficiently by its cushioning springs, so that an even pressure is exerted by the welting ring on the folded or bent-over edge of the hat-brim. The welting ring is preferably made of cast-iron, and provided at its lower edge with a face-plate d^0 of brass, as shown in Fig. 5, the welting ring and its face-plate being thoroughly heated by the heating jets of the gas-arms, so as to exert by combined pressure and heat an effective welting action on the bent-over edge of the hat-brim. The welt is thereby retained in position when the hat is removed from the machine and templet. The welt can be bent over the circumference of the templet, either above or below the same, according as the welt is to be formed at the inside or outside of the brim, the hat shown in the drawing being a military hat, in which the welt is formed on the outside of the edge of the brim.

When the welt is sufficiently worked upon by the welting ring so as to retain its position, the welting ring is locked in position on the table by means of pivoted clamps g , located at opposite points on the table, so that the welt is firmly pressed down on the templet. In this position the cutting off or rounding of the inner edge of the welt is accomplished along the lower edge of the welting ring by means of a cutting knife k , which is guided in an upright holder k^1 and retained by a set-screw k^2 , the holder being provided with a handle h by which it is pressed with its rounded-off face against the inner edge of the welting ring. To the under-side of the holder is applied a tongue h^1 which is attached to the under-side of the handle h , and which is provided with a shoulder h^2 so as to permit the entry of the irregular edge of the welt between the handle and tongue, the tongue being rounded off at its edge so as to pass readily, in connection with the rounded-off face of the holder, around the inner surface of the welting ring and produce by the cutting action of the knife the even cutting off of the edge of the welt, as shown in Figs. 5 and 6. In place of the cutting device shown, any other equivalent cutting means may be employed.

When the machine is used for welting and rounding off army hats, holes have to be punched into the brim near the base of the crown for applying the hat-cords. For this purpose the table a^1 and the base of the stationary ring b are provided at each side of the hat-crown with parallel slots o , in which are placed two punches p , one at each side of the crown. The punches p are supported on base-plates p^1 which are attached to the table a by screws p^2 that are passed through slots o^1 of the base-plates p^1 , as shown clearly in Figs. 5 and 6. The punches are adjustable relatively to the base of the crown and are provided with rounded-off upper ends and placed in register with openings o^2 in the templet at each side of the crown of the hat; so that by a few blows of a mallet the punches pass through the brim and cut clear, neat holes, one at each side of the crown. When the brims of ordinary hats are welted and rounded off on the machine, the holes in the brim are not required, in which case the punches can be removed or retained in position without being used.

The operation of my improved machine for welting and rounding hat-brims is as follows: The hat is placed on the templet and then inserted into position in the oval opening at the center of the table with the crown in downward direction, the bent-over edge of the brim being folded over the outer circumference of the templet. The gas-arms are then moved by means of the swiveled arm over the table and the welting ring is placed in position around the same, as shown in dotted lines in Fig. 1 and in full lines in Fig. 3, so that it is thoroughly heated up by the gas-jets. The welting ring is then lowered by the treadle-rod r against the balance-weight, until its lower edge arrives on the bent-over welt of the hat-brim and presses the same firmly on the templet, as shown in Fig. 5. When the treadle-rod arrives in its lower position, the transverse rod of the guide-rods rests on the lever-rods f and imparts a quickly repeated reciprocating motion to the welting ring, so that the pressure of the ring on the moist welt gives the permanent shape to the welt, according as the same is folded over the outer circumference of the templet. When the welt is formed by the combined action of the heat and pressure of the welting ring the latter is locked in position on the table by turning over the clamping lugs, as shown in Figs. 1 and 2, so as to hold the welt in position on the templet. The cutting knife is then placed in position against the inner surface of the welting ring and moved over the welt and templet, so as to cut off the irregular edge of the welt, as shown in Figs. 5 and 6. During this operation the gas-heating arms are moved to the outside of the table by means of the swiveled supporting arm so as to clear the table and be

not in the way. Simultaneously with this motion the gas-supply cock may be partly closed so that the size of the gas-jets is reduced. The holes are next punched in the 5 brim by the blows of a mallet on the punches, after which the templet is removed with the hat from the machine and the welted and rounded-off hat removed from the templet. Another hat is then placed on the templet 10 and the latter replaced in position in the machine, after which the heating arms are moved over the table again, the welting ring raised and placed around the same for being heated, after which the same welting and 15 rounding-off operation before described is repeated.

The operation of welting the hat-brim and rounding off the edge of the welt is performed in a uniform and reliable manner, so that the 20 skilled hand-work heretofore required for producing these operations is dispensed with and the operations performed by the machine.

Having thus described my invention, I 25 claim as new and desire to secure by Letters Patent:

1. In a machine for welting and rounding hat-brims, the combination, with a table having a templet-opening, and a templet, of 30 a stationary oval ring on said table, a welting ring fitted within the same, means for raising and lowering said welting ring, a heating device for the welting ring, and means for swinging said heating device over the table.

35 2. In a machine for welting and rounding hat-brims, the combination, with a table having a templet-opening, and a templet, of a stationary ring extending around said templet, a welting ring fitted into said stationary 40 ring, and means for imparting a quick reciprocating motion to the welting ring.

45 3. In a machine for welting and rounding hat-brims, the combination, with a table having a templet-opening, and a templet, of a stationary oval ring surrounding said opening and templet, a welting ring fitted into the stationary ring, and means for imparting a

short reciprocating motion to the welting ring for exerting a yielding pressure on the welt of the hat-brim.

50

4. In a machine for welting and rounding hat-brims, the combination, with a table having a templet-opening, and a templet, of a stationary oval ring surrounding said opening, a welting ring fitting into the stationary 55 ring, and means for locking the welting ring to the stationary ring.

5. In a machine for welting and rounding hat-brims, the combination, with a supporting table, of a stationary ring on the same, a 60 welting ring fitted into said stationary ring, means for raising or lowering said welting ring, an angular arm swiveled to one corner of the table, radial gas-heating pipes applied to the upper end of the swiveled arm, and 65 means for supplying gas and air to said heating pipes for heating the welting ring when in raised position.

6. In a machine for welting and rounding hat-brims, the combination, with a table 70 having a templet-opening, of a stationary ring around said opening, a welting ring fitting within said stationary ring, vertically moving guide-rods supporting said welting ring, a counterbalanced treadle connected 75 with said guide-rods, oscillating levers on which said treadle rests, and means for oscillating said levers.

7. In a machine for welting and rounding hat-brims, the combination, with a supporting table, of a hat-carrying templet seated in an opening of the same, said templet being 80 provided with a hole at each side of the crown, and stationary punches attached to the table in register with said holes for punching 85 holes into the hat-brim.

In testimony, that I claim the foregoing as my invention, I have signed my name in presence of two subscribing witnesses.

GUSTAV SEGSCHNEIDER.
